VEHICULAR EMERGENCY LIGHT

Ivan W. Conrad, Alexandria, Va.

Filed May 20, 1958, Ser. No. 50,983

Term of patent 14 years

(Cl. D48—32)

Fig. 1 is a perspective view of a vehicular emergency light showing my new design;

Fig. 2 is a top plan view thereof with the light member omitted for convenience of illustration only; and

Fig. 3 is a bottom plan view thereof as shown in Fig. 2;

The dominant features of my design reside in the portions shown in full lines.

I claim:

The ornamental design for a vehicular emergency light, as shown and described.
